UNITED STATES PATENT OFFICE.

FRITZ SCHORI, OF WETZIKON, SWITZERLAND, ASSIGNOR TO THE FIRM: BAUER A.-G.,
OF ZURICH, SWITZERLAND.

TUMBLER FOR SAFETY LOCKS.

Application filed June 21, 1926, Serial No. 117,307, and in Germany July 29, 1925.

With the tumbler locks heretofore known, double-bit keys could render their full service only in such cases where the tumblers of a series had enough friction between 5 themselves to prevent them from automatically changing their position. As soon as they became loose, a single bit would be sufficient for setting them, because when acting each would be carried alone and by its own 10 weight into the right position for permitting free passage of the bolt. Sometimes tapping or knocking the lock would assist in bringing about this result. It will thus be seen that if a single bit is sufficient the imitation of the lock is rendered much easier and consequently the protection afforded thereby is considerably reduced.

The object of the present invention is to provide a tumbler which requires absolutely 20 both of the bits of an opposed bit key for setting it, thereby greatly increasing the security of the lock. This result is accomplished by making the gating in the tumbler for the fence pin of the bolt normally too 25 small for the passage of said pin, but capable of being enlarged to permit such passage only when both of the key bits are brought into action.

In the accompanying drawing the figure 30 illustrates a face view of the tumbler.

Referring to the drawing, the tumbler is formed of a blank of resilient material provided with a bolt hole *a* in the well-known generally accepted manner, said hole serving 35 to receive the swing bolt. The blank is also provided with an opening *b* for the reception of a double bit key, a gating *c* for the fence pin *d* of a bolt *e*. According to the present invention the width of the gating *c* in the inoperative or normal position of the tumbler 40 is slightly less than the width *f* of the fence pin *d*, so that the latter cannot pass through the gating even though the tumbler may be set in the right position to bring the gating into alinement with the fence pin. The 45 blank is divided longitudinally by slits *g* and *h* into two equal parts *t* and *t'* which are united at one end of the blank by a narrow portion *i*. This permits an elastic spreading 50 of the two parts under the action of the key bits *s¹* and *s²* for enlarging the gating *c* to permit free passage of the fence pin. It is obvious that in order to accomplish this both bits of the key are necessary, because

by the use of a key with a single bit, for 55 instance the bit *s¹* alone, all that would be accomplished would be a rotation of the tumbler while the width of the gating *c* would remain unaltered.

For the purpose of preventing undue enlargement of the gating *c* by the use of too 60 large a key, which might permanently enlarge the gating so as to permit passage of the fence pin, a bridge *m* is carried by one of the parts of the tumbler, for instance, the 65 part *t'* and is provided with a head *l* disposed within an opening *k* of predetermined width formed in the other part *t* of the tumbler, the relative sizes of said head and opening being such as to permit the two parts *t* 70 and *t'* to separate a certain distance and limiting the spreading of the gating to a certain extent. The same result can be accomplished by making only a few of the tumblers of a series in the manner described, the 75 others being provided with the ordinary well-known gating corresponding with the width of the fence pin *f*. In this manner any undesirable spreading of the two parts of the tumblers is avoided.

It will, of course, be readily understood that, instead of making the two parts of the tumbler integral, they may be entirely separate members resiliently connected together 80 in any suitable manner.

It will be seen from the foregoing that the key must be of exactly a certain shape and size, since if it is the slightest bit too small it will not open the gating sufficiently to permit passage of the fence pin. On the 90 other hand, if the key is too large the head *l* of the bridge *m* will prevent turning of the key. Both bits of the key must therefore be absolutely fitted to the lock, so that imitation is rendered extremely difficult.

Having now particularly described the nature of my said invention what I claim as new, and desire to secure by Letters Patent, is:—

1. A lock tumbler, comprising a pair of 100 resiliently united members adapted to move toward and from each other and forming between them a gating for the passage of a fence pin, said gating being normally narrower than the width of the fence pin, said 105 movable members having between them an opening for the reception of a double-bit key, said opening being of such form that

the turning of the key will move the members apart to permit passage of the fence pin.

2. A lock tumbler, comprising a pair of resiliently united members adapted to move toward and from each other and forming between them a gating for the passage of a fence pin, said gating being normally narrower than the width of the fence pin, said 10 movable members having between them an opening for the reception of a double-bit key, said opening being of such form that the turning of the key will move the members apart to permit passage of the fence 15 pin, and means carried by said members for limiting their separating movement.

3. A lock tumbler, comprising a pair of resiliently united members adapted to move toward and from each other and forming 20 between them a gating for the passage of a fence pin, said gating being normally narrower than the width of the fence pin, said movable members having between them an

opening for the reception of a double-bit key, said opening being of such form that 25 the turning of the key will move the members apart to permit passage of the fence pin, one of said movable members having an opening and the other a bridge member provided with a head seated in said opening, 30 the shape and relative sizes of said opening and head being such as to permit only a limited separating movement of said members.

4. A lock tumbler, comprising a blank of resilient material forming a pair of members united at one end by a narrow strip, said members having formed between them a gating and an opening for the reception of a double-bit key, the contour of the walls of said opening being such that the turning 35 of the key will spread the members apart thereby to widen said gating.

In testimony whereof I have signed my name to this specification,

FRITZ SCHORI.
